UNITED STATES PATENT OFFICE.

JAMES DUNLOP, OF CHICAGO, ILLINOIS, ASSIGNOR TO KAESTNER & HECHT COMPANY, OF CHICAGO, ILLINOIS, A CORPORATION OF ILLINOIS.

ELEVATOR-DOOR LOCK.

Application filed August 16, 1924. Serial No. 732,398.

My invention relates to improvements in elevator door locks, and more specifically to door locks controlled by cam means on the elevator cage.

5 One of the objects of my invention is to provide a door lock with a mechanical means for actuating the locking member to release the door catch, said means being operable when the cage is at the landing but being 10 incapable of actually moving the locking member unless an attempt to open the door is made.

Another object is to provide a novel elevator door lock comprising a latch operating 15 means which is adapted to be automatically actuated by a cam on the elevator cage to store up energy for raising the latch, but the action of which is suspended when the door is completely closed.

20 A more detailed object is to provide a flexible latch operating means having a spring which is adapted to be deflected by one member, and with the energy thus obtained to actuate another member.

25 Ancillary objects and advantages will become apparent as the description proceeds.

In the accompanying drawings, Figure 1 is a front view of a door lock constructed in accordance with my invention, one of the 30 cover plates being removed to show the interior.

Fig. 2 is a view showing a slightly different assembly of parts.

Fig. 3 is a sectional view taken along line 35 3—3 of Fig. 1.

Fig. 4 is a left side view of a lock shown in Fig. 2 with the door catch withdrawn.

Fig. 5 is a diagrammatic representation of a simple electrical elevator illustrating the 40 use of the lock.

While my invention is susceptible of various modifications and alternative constructions, I have shown in the drawings and will herein describe in detail the preferred embodiment, but it is to be understood that I do not thereby intend to limit the invention to the specific construction disclosed but aim in the appended claims to cover all forms falling 45 within the spirit and scope of the invention.

50 Referring to the exemplary embodiment illustrated in the drawings, 10 designates a

suitable casing for the door lock which preferably consists of a hollow rectangular frame 11. The opposite sides of the frame 55 11 are connected by two parallel spaced webs 12, and the front and rear faces are closed by removable cover plates 13. One side of the frame 11 is formed with an opening 14 adapted to receive the catch 15 on the door 60 16.

While any suitable means can be employed to secure the casing 10 to the hatchway 17, I prefer to use bolts 18 which extend through 65 bores 19 in the corners of the frame 11. The 13 cover plates 13 are similar but right and left hand in construction, and the bores 19 are beveled at both ends to permit reversal of the casing 10 for doors 16 opening to the right and left.

70 Removably mounted on a pin 20 and between two spaced lugs 21 extending inwardly from one side of the frame 11 is a pivotal locking member or latch 22 having a hook 23 at its free end adapted to engage 75 and retain the catch 15 when the door 16 is closed. A pair of plugs 24 are removably threaded into tapped bores 25 in the lugs 21, and support the opposite ends of the pin 20. To permit removal of the plugs, the 80 cover plates 13 are cut away at 26.

The rear end of the latch 22 is formed integral with an arm 27 extending downwardly from the pivot into a position to be engaged by the forward end of the catch 15 85 when the door 16 is closed. Upon being thus engaged, the arm 27 will move the hook 23 into locking engagement with the catch 15, and hold the same against upward movement until the catch 15 is slightly withdrawn 90 as shown in Fig. 1. Downward movement of the latch 22 is arrested by a pair of lateral extensions 28 projecting toward each other from the cover plates 13. The latch 22 can be manually raised to release the 95 catch 15 by means of a pin 29 removably secured to either side of the latch and projecting through a suitable aperture 30 in either one of the cover plates 13, depending on which one is exposed.

100 Means is provided for automatically raising the latch 21. In the present instance, this means is mechanically controlled, but a lock of similar construction

having an electrically controlled latch operating means is fully disclosed and covered in my copending application, Serial No. 732,399 filed August 16, 1924. Referring to Figs. 1 and 2, a ball or cam roller 31 is rotatably mounted on the pivoted end of the latch 22, and is positioned between the forked arms of a cam member 32 adjustably mounted on a spindle 33. One end of the spindle 33 is journaled in one side of the frame 11, and the other end extends out of the casing 10 through an elongated sleeve or support 34 threaded into the other side of the frame 11. Loosely mounted on the outer end of the spindle 33 is a lever 35, the pivotal end of which is forked and the free end of which carries a cam roller 36 adapted to be engaged by a cam 37 on the cage 38 when the latter is at one of the landings 39. Rigidly but adjustably mounted on the spindle 33 between the forks on the lever 35 is a dog 40. A suitable leaf spring 41 secured to the lever 35 extends into overlapping engagement with the free end of the dog 40, and tends to oscillate the latter when the roller 36 is engaged by the cam 37. It will be seen that the dog 40 will raise the latch 22 upon being oscillated in either direction from a central position, and that the casing 10 can be reversed without affecting the operation of the lock if the roller lever 35 is likewise reversed or rotatably adjusted with the dog 40 through 180°. Upward movement of the latch 22 is opposed by the mass of the door 16 acting through the arm 27. To prevent unlatching of the door 16 until an attempt to open the latter is made, the spring 41 is designed with sufficient strength when flexed to raise the latch 22 against its own weight but not to move the catch 15 outwardly.

The latch operating means is susceptible of being assembled with the lock in a number of ways to adapt the latter to different elevator installations. Thus the lever 35 and dog 40 can be rotatably adjusted on the spindle 33 to properly locate the roller 36 for different positions of the cam 37 on the cage 38. The spindle 33 can also be associated with the latch 22 in any other suitable way than that shown in Fig. 1. For example, in the form shown in Fig. 2, one of the plugs 24 is replaced by the sleeve 34, and the spindle 33 is substituted for the pin 20 to support the latch 22.

Means is provided for preventing movement of the cage 38 away from the landing when the door 16 is open or unlatched. This means comprises a pair of rocker arms 42 and 43 made of insulating material and mounted between the webs 12 on pivot pins 44. The upper end of the rocker arm 42 is formed with a cam portion 45 adapted to be engaged and depressed by the door catch 15

as the latter enters the casing 10. The upper end of the arm 43 is provided with a projection 46 fitting loosely into a notch 47 in the lower end of the arm 27. A pair of contact strips 48 are mounted on adjacent sides of the rocker arms, and are electrically connected by a coil spring 49. Removably mounted in a pair of notches 50 formed in opposite sides of the frame 11 is an insulating board 51 which supports a pair of spring contacts 52 positioned to be engaged by the contact strips 48. Undue flexing of the spring contacts 52 beyond their elastic limit, as by a manual depression of the cam portion 45 or latch 22, is prevented by a pair of upstanding lugs 53 formed integral with the plate 51.

The contact strips 48 and the spring contacts 52 constitute a pair of switches 54 and 55 which are connected in series and are adapted to form part of one of the elevator circuits controlling the movement of the cage 38. It will be seen that upon closing and latching the door both switches will be closed, and that upon subsequently disengaging the cam roller 36 the door 16 will be locked. When the door is open and the latch 22 is raised, both switches will be open; when the door is closed and the latch is raised, switch 55 will be open; and when the door is open and the latch is down, as for example, if the spring 41 became defective, switch 54 will be open to prevent in each instance a closure of the circuit through the switches.

Referring to Fig. 5, I have shown the lock as forming part of a simple elevator system, but it is to be understood that it can be connected in many other systems in any other suitable manner. In the present elevator system, the driving motor for the cage 38 is represented by 56, and the "up" and "down" directional switches for controlling the operation of the motor by 57 and 58 respectively. These switches are adapted to be actuated by means of a car switch 59 having a suitable control lever 60.

To actuate the switch 57, the lever 60 is moved to the left thereby closing the following circuit: from the plus main 61, through wire 62, lever 60, segmental contact 63, wire 64, coil 65, and wire 66 including the switches 54 and 55 to the minus main 67 of the line. The doors 16 must be closed so that the switches 54 and 55 are closed. Closure of the switch 57, closes a circuit through the motor armature as follows: from the wire 62, through the lever 60, variable resistance 68, wire 69, switch contacts 70, wire 71, motor armature, wire 72, switch contacts 73 and wire 74 to the minus main 67. The field 75 of the motor is connected directly across the main lines by wires 62 and 74. The speed of the motor

can be varied by moving the lever 60 along the resistance 68 within the range allowed by the segmental contact 63.

Movement of the lever 60 to the right 5 closes a circuit for the switch 58, as follows: from the plus main 61, through wire 62, lever 60, segmental contact 76, wire 77, coil 78, and wire 66 including the switches 54 and 55 to the minus main. Operation of 10 the switch 58 closes a circuit through the motor armature reverse to the foregoing circuit closed by the switch 57, and as follows: from the wire 62, through the lever 60, resistance 68, wire 69, switch contacts 15 79, wire 72, motor armature, wire 71, switch contacts 80, and wire 74 to the minus main.

The switches 54 and 55 of each door lock in the hatchway 17 are connected in series 20 in the wire 66, and hence control the operation of the directional switches. If the cage 38 is at the landing, the cam 37 will engage the roller 36 to flex the spring 41 and the door 16 will be unlocked. Since the energy in the spring 41 is insufficient to 25 overcome the mass of the door 16, movement of the dog 40 will be suspended until the arm 27 is released by the withdrawal of the door catch 15 against the hook 23. Further movement of the cage 38 is prevented until 30 the door 16 is closed and latched.

It will be seen that I have provided a door lock simple in construction and operation, capable of being assembled and mounted in different ways for different elevators, and efficient and safe in use. While I have shown the casing 10 as secured to the hatchway 17, and the catch 15 to the door 16, it is contemplated that these parts 35 can readily be reversed without affecting the operation of the lock.

I claim as my invention:

1. An elevator door lock having, in combination, a casing, a door catch, a latch in the form of a bell crank one arm of which 45 is provided with a hook to engage said catch and the other arm of which is positioned to be engaged by said catch, the space between said hook and said last mentioned arm being sufficient to allow a limited movement of said catch without raising said latch, and mechanically controlled means for automatically raising said latch, said means being ineffectual when said catch engages said last mentioned arm.

50 2. An elevator door lock having, in combination, a casing, a door catch, a latch in said casing, and mechanical means positioned for engagement by the cage for automatically raising said latch when the cage 55 is at the landing but being ineffectual until an attempt to open the door is made.

50 3. An elevator door lock having, in combination, a casing, a door catch, a latch in said casing mounted to engage said catch and to 60 be held thereby in engagement therewith

when the door is completely closed, and spring means rendered operable when the cage is at the landing to automatically raise said latch, said means being ineffectual until said catch is partially withdrawn.

70 4. An elevator door lock having, in combination, a casing, a door catch, a latch pivotally mounted in said casing and having a depending arm adapted to be engaged by said catch, a spindle mounted in said casing, cam means on said spindle operatively associated with said latch to raise the latter, a lever loosely mounted on said spindle and having a cam roller, a dog rigidly secured to said spindle, spring means carried by said lever 75 and extending into overlapping engagement with said dog to resiliently actuate the latter, and cam means mounted on the cage in a position to engage said roller as said cage moves to the landing, said spring means being incapable upon oscillation of said lever of oscillating said dog to raise said latch until said depending arm is disengaged by said catch.

80 5. An elevator door lock having, in combination, a casing, a door catch, a locking member in said casing for engaging said catch and constructed to be held in locking position by the latter, and mechanically operated means rendered operable when the cage is at the landing but being ineffectual to move said member except after or simultaneously with an attempt to open the door.

85 6. A door lock having, in combination, a casing, a door catch, a latch in said casing, a cam roller on said latch, a spindle, cam means on said spindle positioned to engage said roller upon movement in either direction, and cam actuated means for rotating said spindle.

90 7. An elevator door lock having, in combination, a door catch, a latch for engaging said catch, a spindle operatively associated with said latch to raise the latter upon being rotated, spring means for rotating said spindle, and cam means positioned on the cage to actuate said spring means when the cage is at the landing.

100 8. An elevator door lock having, in combination, a door catch, a latch for engaging said catch, a spindle operatively associated with said latch to raise the latter upon being rotated, a lever having a forked end loosely mounted on said spindle and being provided with a cam roller at its other end, a dog rigidly secured to said spindle between the forks of said lever, a spring tending to move said dog and said lever simultaneously and means for engaging said roller when the cage is at the landing to oscillate said lever.

105 9. In an elevator door lock having a catch and a latch for engaging said catch, a latch operating means comprising, in combination, a spindle adapted to be associated with said 110

125 130

latch to disengage the latter from said catch upon being rotated, a member loosely mounted on said spindle, a second member rigidly secured to said spindle, and a spring tending to oscillate said members simultaneously when said first member is oscillated in one direction.

10. An elevator door lock having, in combination, a door catch, a locking member for engaging said catch, a spindle operatively associated with said locking member to disengage the latter, a member loosely mounted on said spindle, a second member rigidly mounted on said spindle, spring means tending to prevent independent oscillation of

said members, and means acting to oscillate said first mentioned member when the cage is at the landing.

11. In an elevator door lock, in combination, a support, a lever loosely mounted on said support, a second lever mounted on said support next to said first mentioned lever, and a leaf spring secured at one end to one of said levers and engaging the other of said levers with its free end, said leaf spring tending to prevent independent movement of said levers in one direction. 20 25

In testimony whereof, I have hereunto affixed my signature.

JAMES DUNLOP.
